Primary Examiner—Philip S Hyder*Assistant Examiner*—Roselynne Cody*(74) Attorney, Agent, or Firm*—Barkume & Associates, P.C.(57) **CLAIM**

The ornamental design for a bag with attached foldable mat, as shown and described.

DESCRIPTION

FIG. 1 is a perspective view of a bag with attached foldable mat showing my new design;

FIG. 2 is a top view thereof;

FIG. 3 is a front view thereof;

FIG. 4 is a left side view thereof;

FIG. 5 is a right view thereof;

FIG. 6 is a rear view thereof;

FIG. 7 is a bottom view thereof;

FIG. 8 is a perspective view thereof showing the attached mat in an unfolded position;

FIG. 9 is a perspective view thereof showing the attached mat in a partially folded position; and,

FIG. 10 is a perspective view thereof showing the attached mat in a further partially folded position.

The broken line in the figures, indicating stitching, form no part of the claimed design.
